(57) **CLAIM**

The ornamental design for a “packaging for pharmaceutical products”, as shown and described.

DESCRIPTION

FIG. 1 is a top, front and right side perspective view of a first embodiment of a packaging for pharmaceutical products showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a bottom plan view thereof;

FIG. 7 is a top front perspective view illustrating the packaging for pharmaceutical products in an unfolded condition;

FIG. 8 is a plan view of the packaging hereof in the unfolded condition;

FIG. 9 is a right side elevational view of the packaging hereof in the unfolded condition;

FIG. 10 is a front elevational view of the packaging hereof in the unfolded condition;

FIG. 11 is a rear elevational view of the packaging hereof in the unfolded condition;

FIG. 12 is a top, front and right side perspective view of a packaging for pharmaceutical products in accordance with a second embodiment hereof;

FIG. 13 is a front elevational view thereof;

FIG. 14 is a rear elevational view thereof;

FIG. 15 is a right side elevational view thereof;

FIG. 16 is a left side elevational view thereof;

FIG. 17 is a top plan view thereof;

FIG. 18 is a bottom plan view thereof;

FIG. 19 is a top front perspective view thereof illustrating the packaging for pharmaceutical products of the second embodiment in an unfolded condition;

FIG. 20 is a top plan view thereof in the unfolded condition;

FIG. 21 is a bottom plan view thereof in the unfolded condition;

FIG. 22 is a right side elevational view thereof in the unfolded condition;

FIG. 23 is a left side elevational view thereof in the unfolded condition;

FIG. 24 is a front elevational view thereof in the unfolded condition; and,

FIG. 25 is a rear elevational view thereof in the unfolded condition.
